BAG MAKING MACHINE

Adolph Potdevin, Garden City, N. Y., assignor to
 Potdevin Machine Company, Brooklyn, N. Y.,
 a corporation of New York

Application September 12, 1935, Serial No. 40,246

31 Claims. (Cl. 93—26)

This invention relates to bag making machines, and has for one of its objects the provision of a machine wherein a new and improved and simplified construction is employed whereby the 5 machine can be readily accommodated to the making of bags of different lengths, the range of bags capable of being made on this machine being greater than usual bag making machines.

The present invention also provides a construction wherein the completed bags are collected directly from the bottoming mechanism, the bags as they are collected or stacked being counted.

Other objects of the invention will be manifest from the following description and the accompanying drawings.

In the drawings:

Fig. 1 is a more or less diagrammatic view of a machine embodying my invention;

Fig. 2 is an elevational view of the delivery end 20 of the machine;

Fig. 3 is a plan view of the same;

Fig. 4 is a sectional view taken substantially on the line 4—4 of Fig. 2; and

Fig. 5 is an enlarged elevational view of the 25 stacking or bag collecting mechanism.

Referring to the drawings in detail and first of all to Fig. 1, I designate a supply of the material in web form from which the bags are to be made. The web 2 passes from this supply about 30 a roller 3 and from thence past an adhesive applying device comprising a disc 4 contacting the web and transferring paste or glue 6 from the trough 7 to the web.

The web then passes about a roller 9 to tubing 35 mechanism 10 where the web is continuously tubed.

The tubing passes between rollers 20 and feed rollers 22 and from thence to pinch rollers 28 which hold the tubing while the same is cut off 40 into bag lengths by stationary knife 23 and striker bars 24.

During the cutting off operation the forward part of the tubing is momentarily held by the pinch rollers 28 which, as is customary, provide 45 a slack in the tubing during the cutting off operation.

The upper pinch roller is shown as provided on its periphery with pinch blocks 29 and 30 disposed 180° apart, the lower pinch roller being provided with a flattened portion 31 on one side thereof for a purpose to be brought out hereinafter. This lower pinch roller is adjustable circumferentially on its shaft.

The tubes are bottomed on a bottoming drum 55 40 mounted on a shaft 41.

The periphery of the drum 40 is provided with a plurality of equally spaced slots or bottoming stations 44, and adjacent each of these stations there is provided a rock shaft 45 carried by the drum and provided with gripper jaws or gripper plates 46. Each rock shaft is equipped with a cam follower 47 adapted to engage a stationary opening cam 48. As usual in these machines the gripper jaws or plates are spring closed.

Intermediate the pinch rollers 28 and the bottoming drum and on the frame of the machine at a fixed distance from the pinch rollers is a tucker plate cylinder 50 carrying a tucker plate 51 for engaging the face of each bag length a short distance back of the leading end thereof 10 to tuck the same into an adjacent slot or station 44 in the bottoming drum. Just prior to this tucking operation a cam follower 47 at that particular station will have engaged the opening cam 48, so that the gripper jaw adjacent the tucker plate at the time the tucker plate operates 20 is in open position, the gripper jaw or plate, as the cam follower rides off the cam 48, closing on the material of the bag length to attach the same to the drum.

The bag length which is now attached to the bottoming drum is advanced thereby to a paste-applying device mounted beyond the tucker cylinder. This paste-applying device which is mounted on the machine frame just above the bottoming drum, as shown in Fig. 2, comprises a paste pot 55 adjustable by means of a screw 56 and provided with a glue transfer roller 52 mounted for rotation therein. This roller 52 transfers glue to a paster bar 53 which is driven by a shaft 54. As will be brought out hereinafter, the paster bar makes one revolution for each station on the bottoming drum 40, the tucker cylinder 50 making two revolutions for each station. The machine is so timed that the paster bar will engage the face of the bag length behind the turned up end 53' thereof as the bag length passes the paste-applying device. Inasmuch as the tucker cylinder 50 makes two revolutions for each station 44 on the face of the bottoming drum, I provide the face of the drum with slots 40 intermediate the bottoming stations for accommodating the tucker plate 51 between tucking operations, thereby preventing injury to the bag material due to the same being pinched between the tucker plate and the face of the bottoming drum.

In connection with the construction provided and so far described wherein the tucker cylinder 50 is located intermediate the pinch rollers 28 and 55

the paste-applying mechanism, it is to be noted that by separating the tucker cylinder and the paste-applying mechanism, that is, by mounting the tucker cylinder intermediate the pinch rollers 5 and paste-applying mechanism, and by employing a relatively small cylinder 50, bags of very short lengths can be readily handled, the employment of the small diameter tucking cylinder permitting the same to be located very close to the 10 pinch rollers.

When each bag length has been acted on by the paste-applying bar 53 it is carried by the bottoming drum beneath presser roller 57 which presses the upturned end 53' of the bag length 15 down firmly upon the pasted area thereby to finish the bottoming operation.

As mentioned at the outset of this description, the finished bags are collected or stacked directly from the bottoming drum. Referring to this 20 part of my apparatus, 60 designates a cam cooperating with the cam followers 47 of the gripper plates 46 for opening these gripper plates to release the finished bags from the bottoming drum. This opening cam is mounted on an arm 25 61 carried by the shaft 41 of the bottoming drum. The arm 61 has a slight oscillatory movement on the shaft 41, being adjustably secured to a lever 62 mounted on this same shaft, the lever 62 being cam actuated as will be brought out presently to 30 vary the setting of the opening cam 60.

70 designates a shaft extending longitudinally of the machine and carrying the striker bars 24. This shaft 70 carries a large bevel gear 72 meshing with a small bevel gear 71 on the drive shaft 35 42 of the machine, the gearing being 2:1 so that for every revolution of the shaft 70 the drive shaft makes two revolutions. The shaft 70 adjacent its other end is provided with a sprocket 73 which through sprocket chain 74 drives a 40 sprocket 75 mounted on a shaft 76. The sprockets 73 and 75 have a 2:1 ratio, the sprocket 73 being twice the diameter of the sprocket 75.

The shaft 76 carrying the sprocket 75 is provided with a worm 77 meshing with worm wheel 45 78 mounted on a shaft 79 extending transversely of the machine at the rear of the bottoming drum.

The shaft 79 is provided with cams 80 and 81. The cam 80 is adapted to engage a projection 83 on the lever 62 above referred to for actuating 50 the arm 61 which carries the opening cam 60 whereby the setting of the cam 60 will be varied, thereby to vary the opening of the gripper jaws or gripper plates 46 accordingly for a purpose to be later set out.

55 Straddling the shaft 79 is an arm 84 which carries a cam follower 85 cooperating with the cam 81. The outer end of the arm 84 is connected to an arm 86 mounted on shaft 91 for imparting a rocking motion thereto as the arm 84 is actuated 60 by the cam 81. A spring 87 maintains the cam follower 85 in engagement with the cam 81.

Affixed to the shaft 91 is an arm 90 provided at its free end with pivotally mounted counting fingers 92. A spring 88 is secured to the tail of 65 each of these fingers, the other end of these springs being anchored. These springs hold the fingers 92 normally in the position shown in full lines in Fig. 5. The setting of the fingers on their pivots is controlled by a stop screw 88'.

70 The completed bags are delivered by the bottoming drum directly to a table 125 equipped with a counterweighted carriage 126 which provides a backing for the bags as they are delivered on 75 end by the bottoming drum upon the table, the

carriage moving rearwardly, as will be appreciated, as the bag stack builds up.

As shown in Fig. 2 of the drawings the upper pinch roller 28 is provided with two pinch bars 29 and 30, the bar 30 being removable, set 180° apart 5 so that on one revolution of the pinch roller 28 each of the pinch bars will have operated. This construction is employed when tubes shorter than the circumference of the pinch roller are being handled. When tubes longer than the circumference 10 of the pinch roller are being run, the pinch bar 30 is removed.

The bottoming drum 40 is driven off the shaft 70, heretofore referred to and which rotates at one half the speed of the drive shaft 42, through 15 the medium of bevel gear 150 carried by the shaft 70, this gear meshing with bevel gear 151 on shaft 152 extending transversely of the machine. The gear 150 is twice the diameter of the gear 151.

The shaft 152 at its end remote from gear 151 20 carries a gear 153 in constant mesh with bottoming drum gear 154.

The tucker cylinder 50 is provided with a gear 155 meshing with large gear 156 carried on the bottoming drum shaft 41. The shaft 54 for the 25 paster bar 53 is driven from the large gear 156 through the medium of a gear 157 on the paster bar shaft 54. The paster bar gear 157 is twice the diameter of the tucker plate gear 155.

The pinch rollers 28 are geared together 1:1 30 by gears 158. The shaft of the lower presser roller is provided with driving gear 159. The pinch rollers are capable of being driven one revolution for each bottoming station on the drum 40 or one-half a revolution for each bottoming 35 station depending upon whether the tubes being handled are as long at least as the circumference of each of the pinch rollers, in which event only one pinch bar will be employed, or shorter than the circumference of each of the pinch rollers 40 in which event both pinch bars will be employed.

In the first instance, i. e., one revolution of the pinch rollers for each bottoming station, with one pinch bar in use, the driving gear 159 is meshed with a wide faced gear 160 which also 45 meshes with the bottoming drum gear 154. In the second instance, with both pinch bars operative, and pinch rollers rotating one half revolution for each bottoming station, this wide gear 160 is replaced with a compound gear composed 50 of large gear 161 and half size gear 165, the former meshing with bottoming drum gear 154, the latter with the gear 159. The compound gear and the broad faced gear are mounted adjustably and on a bracket 162.

The forwarding rollers 22 are driven from drive shaft 42 through change gear 111, intermediate gear 111' adjustable on the bracket 110 and a gear on the shaft of the lower forwarding roller. The forwarding rollers are geared together 1:1 as will 60 be understood.

The bottoming drum 40, pinch rollers 28, tucker bar cylinder 50, paster bar 53, the bag collecting station, are all mounted for movement as a unit toward and away from the cut-off 65 station on a rack 100 capable of being moved by pinions 103 mounted on a shaft 102 manually rotated through the medium of a handle 101.

The shaft 70 which carries the gear 150 which constitutes the drive gear for the pinch rollers, 70 tucker plate cylinder and paster bar, is splined on the shaft 70, the latter being provided with a keyway 113 so as to permit of adjustment of the parts above referred to toward and away from the cut off station without disrupting the gear 75

train for driving this mechanism. The sprocket 73 for the sprocket chain 74 is also movable along the shaft 70 so that this drive is not disrupted when the rack 100 is operated.

5 In operation and assuming by way of example that the pinch rollers 28 are being driven at such a speed as to make one-half a revolution for each bottoming station 44 of the bottoming drum so that both pinch bars 29 and 30 will operate on 10 each revolution of the pinch rollers, the bag tubing is forwarded by the forwarding rollers 22, past the cutting off station to the pinch rollers and from thence to the bottoming drum.

As the end of the bag tubing comes up to the 15 bottoming drum, the bottoming drum is rotated into position to bring the bottoming station 44 adjacent the tucker plate cylinder 50, the tucker plate 51 engaging the face of the tubing which will now have been severed by one of the striker 20 bars 34, to depress the same into the bottoming station. As the bag length is depressed into the bottoming station it will be gripped by the gripper plate 46, the machine being so timed that as the 25 material of the bag length is tucked into the bottoming station the cam follower 47 of the gripper stop will have ridden off its opening cam 48. The bag length now being attached to the bottoming drum is carried forward thereby to be engaged by the paster bar 53 which engages the 30 upper face of the bag length just behind the turned up end 53' thereof. The pasted bag length is next advanced by the bottoming drum past presser roller 57 which presses over the turned up end 53' of the bag length upon the 35 pasted area of the bag length. This completes the bottoming operation.

On continued rotation of the bottoming drum the completed bag is advanced to the collecting station where the bags are delivered directly by 40 the bottoming drum to the collecting table 125. It will be understood that at this time the cam 60 will be in position to be engaged by the cam follower 47 of the gripper plates to release the completed bags from the drum for direct delivery to 45 the collecting station.

Inasmuch as at regular intervals it is desired to release a bag from the drum earlier than the majority of the bags are released so that the tops of these earlier released bags will extend above 50 the top of the main stack of bags to facilitate counting, the cam 60 must be shifted automatically so as to be in position to be earlier engaged by the tails 47 of the grippers 46.

In Fig. 2 the parts are shown in position where 55 the cam 60 is in its latest releasing position. It will be appreciated, however, that as the cam 60 continues its rotation in an anti-clockwise direction, as viewed in Fig. 2, the high part of the cam will finally ride under the cam follower 83 on the 60 arm 62 to raise the latter and the cam 60 so as to effect to the same degree an earlier opening of the grippers 46. This earlier opening of the grippers 46 has been illustrated in Fig. 2 wherein a bag A has been released considerably earlier 65 than the majority of the bags in the stack of collected bags designated 127 so that the top of this bag A will project beyond the top of the main portion of the stack. The fingers 92 are at this time in the position shown in Fig. 2 and as will 70 be seen from this figure are engaging the elevated bag A to hold the same against the face of the bags ahead of it until several following bags carried by the bottoming drum have been released behind it upon the table 125, after which the 75 fingers 92 may be released and the bag A will

remain in its elevated position due to the pressure of the bags behind it. The result of all this is that a stack of bags will be built up on the table 125, as illustrated in Fig. 5, wherein two bags which are designated 128 have been shown extending above the top of the main stack of bags. 5

With the parts in the position shown in Fig. 2, it will be apparent that on continued rotation of the cam 81 the arm 84, the cam follower 85 of which is in engagement with the face of the cam, 10 will be moved gradually endwise in a direction away from the shaft 79 until it finally reaches the full line position shown in Fig. 5. This will cause the arm 90 to be rocked downwardly to the full line position shown in Fig. 5 carrying with it the 15 fingers 92 as will be appreciated. On continued rotation of the cam 81 the arm 84 will move in the opposite direction under the action of the spring 87, gradually raising the arm 90 and fingers 92 until the arm and fingers have reached 20 the dotted line position shown in Fig. 5. At this time, as will be seen from an inspection of said figure, the fingers are lying in grooves 90' provided for that purpose in the face of the bottoming drum. Each finger, that is to say, the tail of each 25 finger is provided with a stop member or pin 130 and with the fingers in the dotted line position of Fig. 5 these pins are adapted to engage a fixed part of the machine, as shown in that figure, to prevent further upward movement of the fingers. 30

It will be appreciated that during this time, that is to say, from the time the fingers 92 move downwardly and then upwardly to the position in which they are now assumed to be, i. e., the dotted line position of Fig. 5, the cam 80 has 35 moved into position so that the arm 62 has been raised to its extreme uppermost position to move the opening cam 60 into position which will cause the earliest opening of the gripper jaws 46. Likewise, it will be appreciated that the bags at 40 this time are being delivered directly to the collecting station by the bottoming drum to provide evenly stacked bags. When the cam 60 has been moved to its earliest opening position the cam 81 will have moved to a position where a step 129 45 is therein has come abreast of the cam follower 85, with the result that under the action of the spring 87 there will be a quick upward movement of the free end of the arm 90, but inasmuch as stop pins 130 carried by the fingers 92 are held 50 against further upward movement, the fingers will be rocked about their pivots with a sharp motion into the position shown in Fig. 2, so that the upper ends of these fingers will engage the rear 55 face of the earliest released bags which have been designated A, to hold the same against the bags which preceded them, so that the top thereof will project above the top of the bag stack. Just as this happens a cam follower 83 on the arm 62 will drop off of the high part of the cam 80 allowing the opening cam 60 to drop down so that the bags following the bag A will now be later released and will be directly upon the table 125 behind the fingers 92. After a sufficient number of bags have built up behind the elevated bag A so that 60 the pressure of these bags will be sufficient to hold the bag A in its elevated position, the arm 84 is again forced upwardly to the full line position shown in Fig. 5, as above explained, the bags will thereafter be released in the normal way until the fingers 92 are again moved upwardly, as 65 above explained, that is to say, until the fingers 92 go through their next cycle of operation.

It will be seen from all of the foregoing that the present invention provides a bag making ma- 70 75

chine in which the range of bags capable of being handled on a single machine is considerably increased over the range possible with usual bag machines.

5 It will be apparent to those skilled in this art that by mounting the tucker cylinder 50 separately from the paster bar 53 and rotating the same at relatively high speed a small diameter cylinder can be employed, permitting the same 10 to be adjusted closer to the pinch bars 28 than heretofore possible, thereby accommodating the machine to bags of very short lengths.

I have explained above that when the machine is to be accommodated to very short bag lengths, 15 that is to say, bag lengths which are shorter than the circumference of either of the pinch rollers 28 then the compound gear composed of gears 161 and 135 will be employed, in which event the pinch rollers will be driven at a ratio of one half 20 to one, that is to say, will make one half a revolution for each bottoming station on the drum.

When longer bags are to be handled, that is, tubes which are as long at least as the circumference of each of the pinch rollers 28, then the 25 compound gear will be replaced by a wide faced gear 160 so that the pinch rollers will make one revolution for each bottoming station on the bottoming drum.

It will be seen, furthermore, that the present 30 invention provides an arrangement whereby the bottoming drum, pinch rollers, tucker plate cylinder, paster bar, collecting station, etc. may be adjusted as a unit toward and away from the cut-off station, thereby facilitating adjustment 35 of the machine to accommodate bags of varying lengths, this adjustment being effected without disrupting the driving mechanism.

It will be seen, furthermore, that the present 40 invention provides an arrangement in which the bottoming drum delivers the completed bags directly to a collecting station, as distinguished from the more complicated machines heretofore employed in which it is customary to deliver the finished bag to a conveying mechanism of some 45 kind by which the bags are carried along to a collecting station.

It is to be understood that changes may be made in the details of construction and arrangement of parts herein illustrated and described 50 without departing from the spirit and scope of my invention.

What I claim is:—

1. In the making of bags, the method which comprises bottoming successive bag lengths, then 55 positively and directly collecting the completed bags and misaligning a collected bag at regular intervals.

2. In the making of bags, the method which comprises bottoming successive bag lengths, then 60 positively and directly stacking the completed bags on end, while raising the top of a bag of the stack at regular intervals above the tops of the other bags of the stack.

3. In the making of bags, the method which 65 comprises progressively forming a web into a tube as the web is continuously advanced, severing the continuously advancing tubing into bag lengths, bottoming each bag length, positively depositing the bottomed lengths at a collecting station, and 70 at regular intervals during the depositing operation misaligning a deposited bag relatively to the adjacent bags.

4. In the making of bags, the method which 75 comprises progressively forming a web into a tube as the web is continuously advanced, sever-

ing the continuously advancing tubing into bag lengths, bottoming each bag length, positively depositing the bottomed lengths on end upon a collecting station, and at regular intervals maintaining a completed bag in elevated position so 5 that its top is above the tops of the adjacent bags.

5. In a bag making machine, the combination of a bottoming drum, means for temporarily attaching bag lengths to the periphery of said drum for bottoming while rotating therewith, a collecting 10 station in the path of the bags, means for releasing the bags successively for direct delivery to the collecting station as the leading end of each bag reaches said station, and means for misaligning a bag at regular intervals with respect 15 to the other bags.

6. In a bag making machine, the combination of a bottoming drum, means for temporarily attaching bag lengths to the periphery of said drum for bottoming and rotation therewith, a collecting 20 station in the path of the bags as they are carried around by said drum, means for releasing the bags successively for direct positive delivery to the collecting station, and means for retaining the top 25 of a bag of the collected bags at regular intervals raised above the tops of the other collected bags.

7. In a bag making machine, the combination of bottoming mechanism, a collecting station, said bottoming mechanism positively delivering the bottomed bags directly to and stacking the 30 same at the collecting station, and fingers co-operating with the bottoming mechanism and intermittently operable to effect permanent misalignment of a stacked bag at predetermined intervals in the stack. 35

8. A bag making machine, comprising in combination means for continuously advancing bag tubing, means for severing the tubing into bag lengths, mechanism for bottoming each bag length, a collecting station, said bottoming mechanism delivering the bags directly to the collecting station and positively stacking the same, and fingers adapted periodically to hold certain of the stacked bags out of alignment with the remainder of the stack until sufficient bags have been delivered by the bottoming mechanism behind said misaligned bag to hold the latter in such misaligned position. 45

9. A bag making machine comprising in combination means for continuously advancing bag tubing, severing the tubing into bag lengths and for bottoming each bag length, a collecting station, said bottoming mechanism delivering the bags directly to the collecting station and stacking the same, fingers co-operable with said bottoming mechanism, and cam actuated means for controlling said fingers intermittently and momentarily to hold certain of the delivered bags out of alignment with the remainder of the stack. 55

10. A bag making machine comprising in combination tube severing means for severing bag tubing into bag lengths, cooperating pinch rollers, bottoming mechanism in the path of the bag lengths for bottoming the same, said pinch rollers and bottoming mechanism being movable as a 60 unit toward and away from said severing means. 65

11. A bag making machine comprising in combination tube severing means for severing bag tubing into bag lengths, cooperating pinch rollers, bottoming mechanism in the path of the bag 70 lengths for bottoming the same, a collecting station to which the completed bags are delivered directly by said bottoming mechanism, said pinch rollers, bottoming mechanism and collecting sta- 75

tion being movable as a unit toward and away from said severing means.

12. A bag making machine comprising in combination tube severing means for severing bag tubing into bag lengths, cooperating pinch rollers, a bottoming drum for receiving the bag lengths, a tucker plate engageable with each bag length and cooperable with said drum, a paster bar for applying paste to the bag lengths, and a collecting station to which the completed bags are directly delivered by said bottoming drum, said pinch rollers, bottoming drum, tucker plate, paster bar and collecting station being movable as a unit toward and away from said severing means.

13. A bag making machine comprising in combination, tube severing means for severing bag tubing into bag lengths, cooperating pinch rollers, bottoming mechanism in the path of the bag lengths for bottoming the same, a collecting station to which the completed bags are directly delivered by said bottoming mechanism, said pinch rollers, bottoming mechanism and collecting station being mounted on a rack, and means for moving said rack toward and away from the severing mechanism to effect a corresponding unitary movement of said rollers, bottoming mechanism and collecting station.

14. A machine of the class described, comprising in combination means for continuously advancing a web, tube forming mechanism in the path of said web, severing mechanism in the path of the advancing tube for severing the tube into bag lengths, a rotating bottoming drum in the path of the advancing bag lengths having a plurality of slots in its periphery, means for tucking the ends of the bag lengths into said slots, grippers for engaging the tucked end of the bag length to hold the same to the drum during part of the revolution of the drum, a collecting station, a cam for opening said grippers for the release of the bags directly to said collecting station, fingers cooperating with said grippers, and a cam controlling said fingers in timed relation to the opening of said grippers momentarily to hold certain of said bags out of alignment with the other collected bags.

15. In a bag making machine, the combination of bottoming mechanism comprising a rotating drum, grippers carried by said drum for attaching the bag lengths to said drum, an opening cam for said grippers, and an oscillatable arm for automatically varying the setting of said opening cam to effect a variation in the release of the bags from said drum.

16. In a bag making machine, the combination of bottoming mechanism comprising a rotating drum, grippers carried by said drum for gripping bag lengths thereto, a cam for opening said grippers after the bottoming operation, and a cam controlled arm for automatically varying the setting of said opening cam.

17. In a bag making machine, the combination of bottoming mechanism comprising a rotating drum, grippers carried by said drum for attaching the bag lengths to the drum for the bottoming operation, a stationary cam for actuating said grippers initially into open position, an oscillatory cam for opening said grippers at predetermined positions of said drum for release of the bottomed bags from the drum, a cam actuated arm for controlling the position of said oscillatory cam, a collecting station receiving the released bags directly from said drum, and cam controlled means operable in timed relation with the movement of

said oscillatory cam whereby at predetermined intervals a bag will be misaligned with respect to the main portion of the collected bags.

18. In a bag making machine, the combination of a rotatable bottoming drum, grippers carried by said drum for attaching bag lengths thereto, a stationary cam for opening said grippers in the operation of attaching the bag lengths to the drum, an oscillatory cam for opening said grippers at different positions of said drum for the release of completed bags therefrom, a cam actuated arm for controlling said oscillatory cam, and cam-actuated means operating intermittently in timed relation with said oscillatory cam for cooperation with the released bags whereby at predetermined intervals a bag will be misaligned with respect to the remainder of the bags.

19. In a bag making machine, a bag collecting station, a bottoming drum for bottoming bags and delivering the same directly to the bag collecting station, a rock shaft, an arm carried by said shaft, fingers carried by said arm and cooperable with the bags being collected, and a cam for rocking said shaft intermittently to raise and lower said fingers.

20. In a bag making machine, a bag collecting station, a rock shaft, an arm carried by said shaft, fingers carried by said arm, a cam for rocking said shaft to impart an oscillatory motion to said arm periodically to raise and lower said fingers, said cam having a dwell portion for permitting said fingers to remain stationary while bags are being evenly collected, another portion of the cam effecting actuation of said fingers into position to hold certain of the bags being collected out of alignment with the evenly stacked bags.

21. In a machine of the class described, a bag collecting station, a shaft, an arm carried by said shaft, fingers carried by said arm, a bell crank lever on said shaft, a cam for moving said arm to impart a rocking motion to said shaft and an oscillatory motion to said arm periodically to raise and lower said fingers, the dwell of said cam permitting said fingers to remain inactive while bags are being evenly collected, another portion of said cam permitting of a movement of said fingers into engagement with a bag being collected to hold the same out of alignment with the remainder of the collected bags.

22. In a bag making machine, bottoming mechanism, a collecting station cooperating therewith, a rock shaft, an arm carried by said shaft, fingers carried by said arm, a cam for rocking said shaft to impart an oscillatory motion to said arm periodically to raise and lower said fingers, a cam for releasing finished bags from said bottoming mechanism for direct delivery to said collecting station, means for periodically raising and lowering said last mentioned cam thereby to vary the time of release of the bags from the drum, said fingers operating in timed relation to the last mentioned cam whereby the fingers are adapted to engage the earliest released bag to hold the same out of alignment with the remainder of the bags.

23. In a bag making machine, a rotatable bottoming drum, bottoming stations on the periphery of said drum, a rotatable tucker plate for tucking successive bag lengths into successive bottoming stations, said tucker plate rotating at a higher speed than said bottoming drum and out of contact with the periphery of said drum intermediate adjacent bottoming stations.

24. In a bag making machine, a rotatable bot-

bottoming drum, bottoming stations at the periphery of said drum, a rotatable tucker plate for tucking successive bag lengths into successive bottoming stations, said tucker plate making two revolutions between adjacent bottoming stations, the periphery of said drum between adjacent bottoming stations being provided with accommodations for the tucker plate whereby contact of the tucker plate with the periphery of the drum between bottoming stations is avoided.

25. In a bag making machine, the combination of a pair of pinch rollers, a bottoming drum, a plurality of bottoming stations on said drum, a paster bar for applying paste to bag lengths as the same are advanced by said bottoming drum, and a tucker plate intermediate the pinch rollers and said paster bar and cooperating with said bottoming drum, and means for rotating said tucker plate, said tucker plate being overspeeded with respect to the paster bar.

26. In a bag making machine, the combination of a pair of pinch rollers, a bottoming drum, a plurality of bottoming stations on said drum, a paster bar for applying paste to bag lengths as the same are advanced by said bottoming drum, and a tucker plate intermediate the pinch rollers and said paster bar and cooperating with said bottoming drum, and means for rotating said tucker plate, said tucker plate making two revolutions for each revolution of the paster bar.

27. In a bag making machine, the combination of a bottoming drum, bottoming stations on the periphery of said drum, a tucker plate cooperating with said bottoming stations, a paster bar for applying paste to bag lengths as the same are advanced by the bottoming drum, said tucker plate making two revolutions between adjacent bottoming stations, said paster bar making one revolution only between said bottoming stations.

28. In a bag making machine, the combination of a bottoming drum provided with bottom-

ing stations, pinch rollers cooperating with said bottoming drum, and adjustable means for driving said pinch rollers whereby the same may be driven so as to make one half a revolution to each bottoming station or one revolution to each bottoming station.

29. A bag making machine comprising in combination means for continuously advancing a tube, means in the path of said advancing tube for severing the tube into bag lengths, rotatable bottoming mechanism in the path of said advancing bag lengths for bottoming the same, grippers for temporarily attaching the bag lengths to said bottoming mechanism for bottoming and rotation therewith, a collecting station in the path of the bottomed bags, and gripper opening means operable as the leading end of each bag reaches the collecting station to release the bags directly and successively upon the collecting station.

30. In a bag making machine the combination of a bottoming drum, a collecting station immediately adjacent the periphery of said drum, grippers for temporarily attaching successive bag lengths to said drum for bottoming, and gripper opening means operable to open a gripper as the leading end of each bottomed bag reaches the collecting station to release the bags directly and successively upon the collecting station.

31. In a bag making machine the combination of a bottoming drum, grippers for temporarily attaching bag lengths to the periphery of said drum for bottoming and rotation therewith, a horizontally disposed stacking table immediately adjacent the periphery of the bottoming drum, and gripper opening means for said grippers operable to open the grippers as the leading end of each bag reaches the stacking table, to deposit the bags on end successively upon said stacking table.

ADOLPH POTDEVIN.
